DESIGN FOR A CIGARETTE LIGHTER

Hans A. Specht, New York, N. Y.

Application June 11, 1945, Serial No. 120,020

Term of patent 3½ years

(Cl. D48—27)

To all whom it may concern:

Be it known that I, Hans A. Specht, a citizen of the United States, residing at New York, in the county of New York and State of New York, have invented a new, original, and ornamental Design for Cigarette Lighters, of which the following is a specification, reference being had to the accompanying drawing, forming part thereof.

In the drawing:

Fig. 1 the top plan view of a cigarette lighter showing my new design.

Fig. 2 the front elevational view thereof.
Fig. 3 the rear elevational view, and
Fig. 4 is a side elevational view of the cigarette lighter with its cover opened.

I claim:
The ornamental design for a cigarette lighter, as shown.

HANS A. SPECHT.
